UNITED STATES PATENT OFFICE

ARCHIBALD G. SHAVER, OF CHICAGO, ILLINOIS, ASSIGNOR TO THE REGAN SAFETY DEVICES COMPANY, INC., OF NEW YORK, N. Y., A CORPORATION OF NEW YORK

AUTOMATIC TRAIN CONTROL SYSTEM, INTERMITTENT TYPE WITH VEHICLE ENERGY

Application filed January 7, 1922. Serial No. 527,567.

This invention relates to a train control system, and more particularly to a train control system of the induction type, and has special reference to the provision of an induction system arranged to be connected to and influenced by a block signalling system, with the induction system responsive to "safety", "caution" and "danger" track conditions to produce corresponding "clear", "caution" and "stop" effects on the train.

A principal object of the present invention comprehends the provision of an induction train control system in which train carried mechanism is operated to produce a plurality of effects such as proceed, speed restrictive and stop effects responsive to the cooperation between train and track magnetic elements or inductoriums with the train carried mechanism given a "clearing" or test operation in each section or block so as to condition the same for further operation and so as to determine the operability thereof to keep the same in proper working order at all times.

A further principal object of the invention relates to the provision of an induction train control system of the type referred to in which the train and track magnetic elements or inductoriums are operated by train carried energy.

Still further objects of the invention are the provision of an inductive train control system of the nature referred to in which an alternating current or like source of energy is employed, the present invention being particularly an improvement on the induction train control system disclosed and claimed in my copending application Serial No. 422,598 of November 8, 1920, and being coordinate to the induction train control system disclosed and claimed in my copending application Ser. No. 506,595 of October 10, 1921, the present induction system relating particularly to the employment of three-element inductoriums for the vehicle and roadside, the vehicle being provided with a plurality of energy receiving inductoriums for selectively energizing either of a pair of two-position relays, and an energy transmitting inductorium, these inductoriums cooperating with a plurality of track selectively ener-

gized energy transmitting inductoriums and an energy receiving inductorium.

To the accomplishment of the foregoing and such other objects as may hereinafter appear, my invention consists in the elements and their relation one to the other, as hereinafter particularly described and sought to be defined in the claims, reference being had to the accompanying drawings which show a preferred embodiment of my invention, and in which:—

Fig. 1 is a diagrammatic view of the track or roadside mechanism and circuits,

Fig. 2 is a diagrammatic view of the vehicle carried mechanism and circuits, and

Fig. 3 is a diagrammatic view showing a modified arrangement of parts of the track or roadside mechanism.

Referring now more in detail to the drawings, and more particularly to Figs. 1 and 2 thereof, there is provided as disclosed in my copending application above referred to a train control mechanism which comprises the electromagnet M active for controlling the operation of a combined reservoir and brake valve (not shown), the detailed construction of which is set forth in my Patent No. 1,411,526 of April 4, 1922. The electromagnet M is controlled by a two-element relay 35—36; when the currents in the elements 35 and 36 are in phase, as under "clear" track conditions, the contacts 37, 38 and 39 controlled by the relay are caused to assume the full line position shown in Fig. 2; and when the currents are out of phase, as for example 180° out of phase, this existing under "caution" track conditions, the said contacts are caused to assume the inclined dotted line position; and when either of the elements 35, 36 is deenergized, this taking place under "danger" track conditions, the contacts are caused to open and assume a neutral vertical dotted line position shown in Fig. 2.

With this operation of the relay 35—36, under "clear" roadside conditions the electromagnet M is energized to produce a train proceed effect in the valve controlled thereby, the said electromagnet being normally energized from a train carried alternating current source of energy G by the following cir-

95

100

cuit; generator G, conductors 43, 44 and 45, electromagnet M, condenser c, conductor 46, contact 39 in normal full line position, conductor 47, and conductors 48 and 49 to generator G.

Under "caution" roadside conditions the train controlling mechanism M is placed in circuit with a speed circuit controller S so as to produce a vehicle speed restrictive effect, the electromagnet M being energized when the train is proceeding below and being deenergized when the train is proceeding above a predetermined or permissive speed, the said circuit including the generator G, conductors 43, 44 and 45, electromagnet M, the condenser c, conductor 46, contact 39 in inclined dotted line position, conductor 50, contact 51 of speed circuit controller S, conductor 52, and conductors 53 and 49 to generator G. With this arrangement, it will be seen that when the train is moving above the permissive speed the contact 51 will be opened to deenergize the magnet M, and when the train is proceeding below or at the permissive speed, said contact 51 will be closed to energize the magnet M for maintaining the air brake inoperative. The condenser c is provided in the magnet circuit to bring the said circuit into a state of resonance as nearly as possible.

Under "danger" track conditions with the contact 39 in neutral position, the circuit to the electromagnet M is opened, the electromagnet deenergized and the valve controlled thereby operated to set the brakes of the train and to disconnect the engineer's brake valve from the main reservoir as disclosed in my above mentioned Patent No. 1,411,526.

For normally maintaining the relay contact 39 in either of its full or inclined dotted line positions to maintain the unlimited speed or restrictive speed effects on the train, I provide a stick circuit including one element of the relay 35-36 and controlled by another relay 24. For normal or unlimited speed conditions the stick circuit comprises the generator G, conductor 54, contact 25 normally held closed by energization of relay 24, resistance R, conductor 55, contact 37 in full line position, conductor 56, conductors 57 and 58, the coil of relay element 36, conductor 59, condenser c', conductors 60, 81 and 61, contact 38 in full line position, conductor 62, resistance R', contact 26 held normally closed by relay 24, and conductor 63 to generator G. The element 35 of relay 35-36 is energized through the circuit including the generator G, conductors 43 and 64, condenser c' and conductor 49 to generator G. Under these normal conditions the currents in the elements 35 and 36 are in phase and the contacts 37, 38 and 39 are maintained by the relay elements in the full line position by these circuits. The resistances R and R' are provided for protecting against momentary short

circuit of the circuit to the generator G under certain conditions of operation.

When the currents in the elements 35 and 36 differ by 180° in phase, this being a condition produced by means to be described hereinafter, the contacts 37, 38 and 39 are moved to the right hand dotted line position and are retained in this position by the train stick circuit comprising generator G, conductor 54, contact 25 normally closed, resistance R, conductor 55, contact 37 closed in dotted line position, conductor 60, condenser c', conductor 59, relay element 36, conductors 58, 57, 65 and 66, contact 38 in dotted line position, conductor 62, resistance R', contact 26 normally closed, and conductor 63 to generator G. With this circuit it will be noted that the currents in the elements 35 and 36 differ by 180° in phase, and the stick circuit will therefore maintain the contacts 37 to 39 in their inclined dotted line positions.

Under "danger" track conditions, the described stick circuit is broken by the opening of the contacts 25 and 26 controlled by the relay 24 in a manner to be described presently, and the contacts 37 to 39 inclusive assume the vertical dotted line positions with the result that the electromagnet M is deenergized for application of the brakes of the train.

For controlling the positioning of the contacts 37 to 39 of the relay 35-36 so as to impress upon the train controlling means M a desired effect, I provide cooperating vehicle and roadside magnetic means or elements, and more specifically vehicle and roadside inductoriums, the roadside inductoriums being preferably under the control of a block signalling system and being influenced by the same to respond to "safe", "caution" and "danger" track conditions and to indicate such conditions, and the vehicle inductoriums being arranged for movement over the roadside inductoriums to cooperate with the latter to receive and transmit indications of the same to the train circuits and more specifically to the relay 35-36 to correspondingly influence and operate the same. To these ends I provide a train transmitting inductorium 27 connected to the vehicle source of energy G by means of the conductors 43, 67, 68, 69, 70, 71, 53 and 49, a condenser c' for providing a resonant circuit being preferably included in this line of connection; and for cooperation with the train transmitting inductorium 27 I provide a plurality of train energy receiving inductoriums 28 and 29, the inductorium 28 being connected to influence a relay 29 by means of the conductors 72 and 73, the inductorium 29 being connected similarly to influence a second relay 32 by means of the conductors 74 and 75, condensers 76 and 77 being preferably provided in the circuits of the inductoriums 28 and 29 respectively to render the circuits resonant.

For cooperation with the train transmit-

ting and receiving inductoriums, I provide sets of roadside receiving and transmitting inductoriums, a set for each section or block of the track such as A, B and C shown in Fig. 1, each set comprising an energy receiving inductorium 1 and a plurality such as a pair of energy transmitting inductoriums 2 and 16, the energy receiving inductorium 1 being arranged for cooperation with the vehicle transmitting inductorium 27, and the energy transmitting inductoriums 2 and 16 being correspondingly arranged for cooperation with the vehicle receiving inductoriums 29 and 28 respectively, the said track or roadside transmitting inductoriums 2 and 16 being adapted to be selectively connected to and selectively energized by the roadside energy receiving inductorium 1, the said selective energization being made responsive to track or roadside conditions.

For selectively operating the inductoriums 2 and 16 from the inductorium 1, there are provided roadside circuits controlled by a distant relay 8 and a home relay 5 for each block, the construction being such that normal energization of the relays 5 and 8 will effect the connection between the inductoriums 1 and 2, while deenergization of the distant relay 8 responsive to "caution" track conditions will effect the breaking of connections between the inductoriums 1 and 2 and the making of connections between the inductoriums 1 and 16, while the deenergization of relay 5 responsive to "danger" track conditions, both the energy transmitting inductoriums 2 and 16 will be disconnected from the track inductorium 1.

Thus under "clear" track conditions the inductoriums 1 and 2 are electrically connected by means of the circuit including the coil of the inductorium 1, the conductor 3, the contact 4 normally closed by energization of the home relay 5, conductor 6, contact 7 attracted by relay 8, conductor 9, coil inductorium 2, conductor 10, contact 11 in attracted or upper position, conductor 12, contact 13 closed, conductor 14, condenser 15, and the coil of relay 1.

With the relay 8 deenergized under "caution" track conditions, the contacts 7 and 11 will be released for connecting the inductorium 1 to inductorium 16 by means of the circuit including the inductorium 1, conductor 3, contact 4, conductor 6, contact 5 in released position, conductor 17, inductorium 16, conductor 18, contact 11 in released position, conductor 12, contact 13, conductor 14 and condenser 15.

Under "danger" track conditions when the home relay 5 is deenergized the contacts 4 and 13 will be opened for disconnecting the inductorium 1 from both the inductoriums 2 and 16.

The home and distant relays 5 and 8 are made responsive to "clear", "caution" and

"danger" track conditions in a well-known manner, the relay 5 being connected to the track rails and energized by a track battery 6 for each block or section of the block, and the distant relay 8 of one block such as block B being connected to be controlled by the home relay 5 of the next succeeding block by means of a circuit including the conductor 21, armature 19 controlled by the relay 5 of the next succeeding block, battery 20, and conductor 22.

With this construction it will be seen that in the movement of the train or vehicle and in the passage of the vehicle inductoriums over the track inductoriums, an impulse will be transmitted from the train transmitting inductorium 27 to the track receiving inductorium 1, and that such impulse may be selectively transmitted to either of the track transmitting inductoriums 2 and 16 or that the transmission of such impulse may be inhibited for in turn selectively influencing either of the train receiving inductoriums 29 and 28 under "safe" or "caution" conditions, or for not influencing the same as under "danger" conditions, the cooperation between the train and track inductoriums being controlled by a circuit make and break and a pole changing device which are in turn influenced by the home and distant relays 5 and 8 of a block signalling system. It will be noted that the cooperation between the train and track inductoriums is momentary as the former moves over the latter in the movement of the vehicle.

Controlled by the relay 29, there are provided contact armatures 30 and 31 which under normal conditions assume the vertical full line positions shown in Fig. 2 due to the normal deenergization of the relay 29, the said contacts being moved to the dotted line position shown when the relay 29 is energized by the cooperation of the inductoriums 28 and 16. Controlled in a similar manner by the relay 32 there are provided the contact armatures 33 and 35 which under normal conditions also assume the vertical dotted line positions shown in the figure due to the normal deenergization of the relay 32, the said contacts being moved to the full line positions shown when the relay 32 is energized by the active cooperation between the inductoriums 29 and 2.

When under "safe" track conditions the inductoriums 29 and 2 cooperate for energy transference therebetween, the contacts 33 and 34 are made to momentarily assume a full line position by reason of the energization of the relay 32, the momentary closing of said contacts being effective for momentarily energizing the relay element 36 with a current in phase with the current energizing the relay element 35 by means of the circuit comprising the generator G, conductors 43, 44 and 79, contact 34 closed, conductors 80,

66, 65, 57 and 58, relay element 36, conductor 59, condenser c' , conductors 60, 81, 82, contact 38 closed, and conductors 71, 53 and 49 to generator G. By the momentary closing of 5 this circuit, the energization of the relay 35-36 causes the armatures 37 to 39 to assume the full line position shown to close the stick circuit and the circuit of the electromagnet M, producing "clear" or "proceed" conditions 10 on the train.

When under "caution" track conditions the inductoriums 28 and 16 cooperate for energy transference therebetween, the contacts 30 and 31 are actuated to momentarily 15 assume the dotted line position shown, this momentary closing of the contacts effecting the closing of the circuit to a relay element 36 for energizing the same with current differing 180° in phase with the current normally 20 energizing the relay element 35 by means of the circuit comprising generator G, conductors 43 and 67, contact 30 closed, conductors 83 and 60, condenser c' , conductor 59, relay element 36, conductors 58, 57, and 65, contact 25 31 closed, and conductors 84 and 49. With the closing of this circuit the element 36 is energized as referred to by current of a phase opposite to that in element 35, and the contacts 37 to 39 are moved to the inclined dotted line position to close the stick circuit and the circuit including the electromagnet M 30 and the speed controller S, producing "caution" or speed restrictive conditions on the train.

35 When under "danger" track conditions neither of the relays 29 and 32 is energized, both of the operating circuits for the relay element 36 remain unenergized, and should the contacts 37 to 39 be in the vertical dotted 40 line position, said contacts will remain in such position for producing a "stop" effect on the train.

For the purpose of conditioning the vehicle carried mechanism for operation and control 45 by the train and track inductoriums so that the train circuits are made to respond to the indications of the track inductoriums, and for the further purpose of automatically giving the train control apparatus a test operation 50 in each section or block in order to automatically check the operability of the same at all times, there are provided cooperating train and track magnetic means for periodically deenergizing the relay 35-36, and more specifically for opening the stick circuit thereof 55 at the contacts 25 and 26. To this end the relay 24 heretofore mentioned is provided, the said relay being connected to be normally energized from the train source of energy G 60 by means of the circuit including the said source of energy, conductor 54, coil of relay 24, condenser c_4 , conductor 85, inductorium 23, and conductors 86, 48 and 49, the condenser c_4 being preferably provided in this 65 circuit for placing said circuit normally in

a state of resonance. The inductorium 23 constitutes or comprises a trip device for the train circuits the said inductorium cooperating with an inert track element E provided for each section or block of the track, the cooperation between the inductorium 23 and a track element E taking place when the former moves over the latter in the movement of the vehicle, the cooperation being such that when the inductorium 23 moves over an inert element E, the state of resonance of the circuit including said inductorium is destroyed, such that the voltage at the terminals of the relay 24 is considerably decreased. The adjustment 70 of the contacts 25 and 26 of this relay 24 is such that with the circuit in a state of resonance, the contacts are closed, but with the decreased voltage produced when the state of resonance of the circuit is destroyed, the contacts 25 and 26 are opened for opening the stick circuit controlled thereby. With this construction it will therefore be seen that normally when the train is running between track elements E-E, the train circuits when running under "safe" or "caution" conditions 75 will be so maintained by the closing of the stick circuit, and when the inductorium 23 covers a track element E the said stick circuit will be broken and the relay 35-36 will be deenergized, causing the contacts 37 to 39 thereof to move to neutral position for producing "stop" effects on the train, the inductorium 23 and inert track element E comprising 80 therefore a tripping mechanism for the train circuits, conditioning the same for response to the operation of the train and track inductoriums heretofore described, the train and track inductoriums being brought into cooperative relation substantially when or immediately after the tripping operation 85 takes place, the time interval between the tripping operation and the operation of the inductoriums being insufficient to permit the brakes of the train to be set, the inductoriums functioning as a resetting or controlling 90 mechanism for the train circuits responsive to traffic conditions.

The operation of the system thus far described will in the main be apparent from the above detailed description thereof. It 95 will be seen that in each section or block the inert magnetic element E of the track mechanism will momentarily destroy the resonance of the circuit of the inductorium 23, causing a deenergization of relay 24 and an opening 100 of the stick circuit to the relay element 36 for effecting the release of the contacts 37 to 39. Immediately after this action the train and track inductoriums are brought 105 into cooperation to determine the further state of operation of the relay element 36. Under "safe" track conditions an impulse is transmitted to the train receiving inductorium 29 to momentarily operate the reset 110 relay 32 to actuate the contacts 28 and 84, 115

120

125

130

this in turn closing a circuit to the relay element 36 to energize the same with "in phase" current, such energization resulting in the contacts controlled thereby assuming their full line position for closing the stick circuit and the circuit to the electromagnet M, the said stick circuit being thereafter maintained closed by the reenergization of the relay 24 due to the passage of the inductorium 23 beyond the track element E. Under "caution" track conditions an impulse will be transmitted to the train inductorium 28 for momentarily energizing the relay 29, this effecting the momentary closing of an energizing circuit to the relay element 36 with current differing 180° in phase from the current in element 35 for moving the contacts 37 to 39 to their inclined dotted line positions, placing the train under speed restrictive operation. Under "danger" track conditions, no impulse is transmitted to the train inductoriums, with the result that the relay element 36 remains deenergized and the contacts controlled thereby remain in neutral circuit opening position for bringing the train to a halt.

After the train has been brought to a halt, the same may be again set in motion by the operation of a release key 38a, which is placed or located in a normally inaccessible position, operated by the engineer so as to cause the contact elements thereof to connect the generator G to the relay element 36 for energizing the latter with current differing 180° in phase from the current in element 35 by means of a circuit including generator G, the upper contact of key 38a, conductor 58, relay element 36, conductor 59, condenser c', conductors 60, 81 to lower contact of push key 38a and conductor 54 to generator G, this connection causing the energization of the relay element 36 with the 180° out of phase current so that the armature contacts controlled thereby will be moved to the inclined dotted position, thus placing the speed circuit controller in circuit with the electromagnet M so that the train can proceed under or at a predetermined speed only.

Referring now to Fig. 3 of the drawings, I show a construction in which in lieu of tripping the train circuits in each block or in each section of the block as heretofore described, the said circuits may be tripped only when a "stop" condition is to be imposed upon the vehicle. The object of the arrangement shown in Fig. 3 is thus to obviate imposing of the "stop" condition on the vehicle excepting when a condition requiring the train to stop exists. To accomplish this a winding is placed upon the magnetic trip element E', such that when a control relay, as the track relay 5, is energized as under normal conditions, the coil surrounding the track element E' is closed upon itself through the circuit

including coil 40, conductor 41, armature 42 closed, and conductor 88. When in this condition the inductorium 23 comes into correspondence with or moves over the track element E', the state of resonance existing in the circuit of the train relay 24 is not sufficiently disturbed to operate the relay, but when the track relay 5 is deenergized so that the contact 42 is opened, then the operation of element E' is the same as that of element E heretofore described, a tripping of the train circuits being then effected.

Therefore the tripping inductor of Fig. 3 operates to trip or deenergize the vehicle circuits or the vehicle carried apparatus only under roadside stop conditions. When the vehicle carried apparatus is thus tripped or deenergized the train is brought to a halt; and the same may be again set in motion by the operation of the release key 38a as heretofore described, this operation placing the vehicle carried apparatus in the "caution" running position so that the train proceeds under a speed restriction. With the train running under "caution" conditions no change in vehicle carried circuits will be effected when the train moves into a "caution" block since the roadside inductive system under "caution" conditions transmits the "caution" condition which already exists on the vehicle carried apparatus by the said operation of the release key 38a.

The clearing or reenergizing of the vehicle carried circuits or vehicle carried mechanism with the train running under the imposed "caution" operation is effected when the vehicle moves into a clear block by the closing of the clearing inductors such as the roadside inductor or inductorium 2. This is accomplished even though the trip element E of Fig. 3 is in closed circuit. With the circuit of the clear inductor 2 closed, energy is transmitted to the vehicle carried receiving inductor 29 for operating the relay 32 which closes the contacts 33 and 34, this closing of these contacts resulting in energizing the relay element 36 with a "clearing" current, that is, with a current of a phase opposite to that flowing therein through the "caution" circuit thereof. It will be noted that the "caution" circuit contains the resistances R and R' so that the two currents in the relay element 36 not only oppose each other under this clearing condition but the current in the clearing circuit (the circuit of contacts 33 and 34) is of a value larger than the current in the imposed "caution" circuit (the circuit including the resistances R and R');

and the net result is that the clearing circuit is effective first in effectively deenergizing the relay element 36, and second in energizing the same with clearing current such that the contact elements thereof are moved from the "caution" to the "clear" position. Thus the imposed "caution" opera-

tion of the train carried mechanism is changed to the "clear" operation.

When the train running under "clear" conditions enters a "caution" block, the vehicle carried mechanism or circuits are operated to the "caution" position, this being accomplished by the energization of relay 29 to close the contacts 30 and 31 and this being effective for substituting the "caution" circuit of the relay element 36 for and in lieu of the then existing "clear" circuit thereof. It will be again noted that the then existing "clear" circuit includes the resistors R and R' so that the two currents in the relay element 36 not only oppose each other under this "caution" producing condition but the current in the substituting "caution" circuit (the circuit of the contacts 30 and 31) is of a value larger than the current in the "clear" circuit of the relay element 36 and therefore dominates the same. The net result is that the substituting "caution" circuit is effective first in effectively deenergizing the relay element 36, and second in energizing the same with "caution" producing current such that the contact elements thereof are moved from the "clear" position to the "caution" position.

While I have shown my device in the preferred form, it will be apparent that many changes and modifications may be made in the structure disclosed, without departing from the spirit of the invention, defined in the following claims.

What I claim as new is:

1. In combination, vehicle carried mechanism, means including roadside mechanism for influencing the vehicle carried mechanism in the movement of the vehicle over a roadway, and means for determining the operation of the said mechanism so influenced including a plurality of independent vehicle energy receiving inductor coils and a plurality of roadside energy transmitting inductor coils selectively operable for selectively affecting the vehicle energy receiving inductor coils.

2. In combination, vehicle carried mechanism, means including roadside mechanism for periodically influencing the vehicle carried mechanism in the movement of the vehicle over a roadway, and means for periodically determining the operation of the said mechanism so influenced including a plurality of independent vehicle energy receiving inductor coils and a plurality of roadside energy transmitting inductor coils selectively operable for selectively affecting the vehicle energy receiving inductor coils.

3. In combination, vehicle carried mechanism, means including roadside mechanism for influencing the vehicle carried mechanism in the movement of the vehicle over a roadway, and means for determining the operation of the said mechanism so influenced including a plurality of vehicle energy receiv-

ing inductor coils and a plurality of roadside energy transmitting inductoriums selectively operable for selectively affecting the vehicle energy receiving inductoriums, a source of energy and provisions for selectively energizing the transmitting inductoriums from said source of energy.

4. In combination, vehicle carried mechanism, means including roadside mechanism for influencing the vehicle carried mechanism in the movement of the vehicle over a roadway, and means for determining the operation of the said mechanism so influenced including a plurality of vehicle energy receiving inductors and a plurality of roadside energy transmitting inductors selectively operable for selectively affecting the vehicle energy receiving inductors, and a vehicle source of energy for said inductors.

5. In combination, vehicle carried mechanism, means including roadside mechanism for influencing the vehicle carried mechanism in the movement of the vehicle over a roadway, and means for determining the operation of the said mechanism when so influenced including a plurality of vehicle energy receiving inductors, a vehicle energy transmitting inductor, a plurality of cooperating roadside energy transmitting inductors, a cooperating roadside energy receiving inductor, and a vehicle source of energy connected to the vehicle transmitting inductor.

6. In combination, vehicle carried mechanism, means including roadside mechanism for influencing the vehicle carried mechanism in the movement of the vehicle over a roadway, and means for determining the operation of the said mechanism when so influenced including a plurality of vehicle energy receiving inductors, a vehicle energy transmitting inductor, a plurality of cooperating roadside energy transmitting inductors, a cooperating roadside energy receiving inductor, a vehicle source of energy connected to the vehicle transmitting inductor, and for selectively connecting the roadside receiving inductor to either of the roadside transmitting inductors.

7. In combination, vehicle carried mechanism and means for controlling the operation thereof comprising a plurality of vehicle energy receiving inductors and a plurality of roadside energy transmitting inductors selectively operable for selectively affecting the vehicle energy receiving inductors to produce selectively different operations of said means, a vehicle carried source of energy, and provisions for selectively energizing said transmitting inductors from said source of energy.

8. In combination, vehicle carried mechanism, and means for controlling the operation thereof comprising a plurality of vehicle energy receiving inductors, a plurality of roadside energy transmitting inductors se-

lectively operable for selectively affecting the vehicle energy receiving inductors, and a vehicle carried source of energy for energizing said receiving and transmitting inductors.

9. In combination, roadside apparatus for impressing roadside conditions on moving vehicles, comprising a plurality of roadside energy transmitting inductors and an energy receiving inductor selectively connectible to said transmitting inductors.

10. In combination, roadside apparatus for impressing roadside conditions on moving vehicles comprising a plurality of roadside energy transmitting inductors, a roadside energy receiving inductor, and means for selectively connecting the said receiving to the said transmitting inductors.

11. In combination, roadside apparatus for impressing roadside conditions on moving vehicles comprising a pair of energy transmitting inductors, an energy receiving inductor, means for selectively connecting the said receiving inductor to either of the said transmitting inductors, and provisions for disconnecting the receiving from both of said transmitting conductors.

12. In combination, roadside apparatus for impressing roadside conditions upon moving vehicles comprising a pair of energy transmitting inductors and an energy receiving inductor selectively connectible to either of said energy transmitting inductors.

13. In combination, roadside apparatus for impressing roadside conditions on moving vehicles, comprising roadside means for effecting a controlling condition upon the vehicle and roadside mechanism for modifying such condition, the said roadside mechanism comprising a plurality of energy transmitting inductors and an energy receiving inductor selectively connectible to said transmitting inductors.

14. In combination, roadside apparatus for impressing roadside conditions on moving vehicles, comprising roadside means for effecting a controlling condition upon the vehicle and roadside mechanism for modifying such condition, the said roadside mechanism comprising a plurality of energy transmitting inductors, an energy receiving inductor, and means for selectively connecting the said energy receiving to the said energy transmitting inductors.

15. In combination, vehicle carried mechanism including a train controlling means and a speed controller, means including magnetic roadside mechanism for influencing the train controlling mechanism in the movement of the vehicle, means for determining the operation of the train controlling means so influenced including a plurality of vehicle energy receiving inductor coils, a plurality of roadside energy transmitting inductor coils selectively operable for selectively affecting

the vehicle inductor coils, and provisions for placing the train controlling means under the control of the speed controller when one of said receiving inductor coils cooperates with one of said transmitting inductor coils for energy transference therebetween.

16. In combination, vehicle carried mechanism including a train controlling means and a speed controller, means including roadside mechanism for influencing the train controlling means in the movement of the vehicle, means for determining the operation of the train controlling means so influenced including a plurality of vehicle energy receiving inductors, a plurality of roadside energy transmitting inductors selectively operable for selectively affecting the vehicle energy receiving inductors, a vehicle source of energy for said receiving and transmitting inductors, and provisions for placing the train controlling means under the control of the speed controller when one of said receiving inductors cooperates with one of said transmitting inductors for energy transference therebetween.

17. In combination, vehicle carried mechanism including a train controlling means and a speed controller including roadside mechanism for influencing the train controlling means in the movement of the vehicle to produce a "danger" effect therein, means for determining the operation of the train controlling means so influenced for modifying the effect under "safe" and "caution" track conditions to produce proceed and speed restrictive effects therein, the latter means comprising a plurality of vehicle energy receiving inductors, a plurality of roadside energy transmitting inductors selectively operable for selectively affecting the vehicle energy receiving inductors, and provisions for placing the train controlling means under the control of the speed controller when one of said receiving inductors cooperates with one of said transmitting inductors in response to "caution" track conditions.

18. In combination, roadside apparatus for impressing roadside conditions on moving vehicles comprising a plurality of roadside energy transmitting inductors, a roadside energy receiving inductor, and means for selectively connecting the said receiving inductor to the said transmitting inductors, the said means comprising a pole changer under the control of the distant relay of a signalling system.

19. In combination, roadside apparatus for impressing roadside conditions on moving vehicles comprising a pair of energy transmitting inductors, an energy receiving inductor, means for selectively connecting the said receiving inductor to either of the said transmitting inductors, and provisions for disconnecting the receiving inductor from both of said transmitting inductors, the said

- means comprising a pole changer under the control of the distant relay of a signalling system, and said provisions comprising a make and break device under the control of the home relay of the signalling system.
20. In combination, vehicle carried mechanism, cooperative magnetic vehicle and roadside means for producing a controlling condition in said mechanism under "stop" traffic conditions only, and additional cooperative magnetic vehicle and roadside means for influencing said mechanism to modify the controlling condition under "proceed" traffic conditions.
21. In an inductive train control apparatus, vehicle carried mechanism, mechanism including roadside inductorium means for producing a controlling condition in the vehicle carried mechanism under "stop" traffic conditions only, said roadside inductorium comprising a magnetic core, a winding thereon and a circuit for said winding controlled in accordance with traffic conditions, and mechanism including additional roadside inductorium means for influencing the vehicle carried mechanism to modify the controlling condition under "proceed" traffic conditions.
22. In combination, vehicle carried mechanism, cooperative vehicle and roadside means for producing a controlling condition in said mechanism under "danger" traffic conditions only, and additional vehicle and roadside means for influencing the said mechanism to modify the controlling condition under "safety" and "caution" traffic conditions.
23. In combination, vehicle carried mechanism, cooperating vehicle and roadside means for producing a controlling condition in said mechanism under "danger" traffic conditions only, and additional vehicle and roadside means for selectively influencing the said mechanism to modify the controlling condition under "safety" and "caution" traffic conditions.
24. In an inductive train control apparatus, vehicle carried mechanism, mechanism including roadside inductorium means for producing a controlling condition in the vehicle carried mechanism under "danger" traffic conditions only, and mechanism including additional roadside inductorium means for selectively influencing the vehicle carried mechanism to modify the controlling condition under "safety" and "caution" traffic conditions.
25. In a train control system, vehicle carried mechanism, means including roadside mechanism for producing a controlling condition in the vehicle carried mechanism under a predetermined traffic condition only, and means for modifying the controlling condition under a given traffic condition, the said means including cooperating vehicle and roadside magnetic elements and a vehicle carried source of energy for energizing the vehicle magnetic element by way of the roadside magnetic element.
26. In a train control system, vehicle carried mechanism, means including a roadside inductor for producing a controlling condition in the vehicle carried mechanism under a predetermined traffic condition only, said roadside inductor embodying a magnetic core, a winding thereon and a roadside circuit for said winding controlled in accordance with traffic conditions, and means for modifying the controlling condition under a given traffic condition, the said means including cooperating vehicle and roadside inductors and a vehicle carried source of energy for energizing the vehicle inductor by way of the roadside inductor.
27. In a train control system, vehicle carried mechanism, means including roadside mechanism for producing a controlling condition in the vehicle carried mechanism under a predetermined traffic condition only, roadside mechanism including a magnetic core, a winding thereon and a roadside circuit of low reluctance for said winding controlled in accordance with traffic conditions, and means for modifying the controlling condition under a given traffic condition, the said means including a plurality of vehicle carried receiving inductors, a plurality of roadside transmitting inductors, and a vehicle carried source of energy for energizing the same.
28. In a train control system, vehicle carried mechanism, means including roadside mechanism for producing a controlling condition in the vehicle carried mechanism under a predetermined traffic condition only, and means for modifying the controlling condition under a given traffic condition, the said means including a plurality of vehicle carried receiving inductors, a plurality of roadside transmitting inductors, a roadside receiving inductor cooperating with the roadside transmitting inductors and a vehicle carried energy transmitting inductor cooperating with the roadside receiving inductor.
29. In a train control system, vehicle carried mechanism, means including roadside mechanism for producing a controlling condition in the vehicle carried mechanism under a predetermined traffic condition only, and means for modifying the controlling condition under a given traffic condition, the said latter means comprising a vehicle carried receiving inductorium and a roadside transmitting inductorium cooperating therewith.
30. In a train control system, vehicle carried mechanism, means including a roadside inductor for producing a controlling condition in the vehicle carried mechanism under a predetermined traffic condition only, said roadside inductor embodying a magnetic core, a winding thereon and a roadside circuit for said winding controlled in accordance with traffic conditions, and means for modifying

means comprising a pole changer under the controlling condition under a given traffic condition, the said latter means comprising a vehicle carried receiving inductorium and a roadside transmitting inductorium cooperating therewith.

31. In a train control system, vehicle carried mechanism, means including roadside mechanism for producing a controlling condition in the vehicle carried mechanism under a predetermined traffic condition only, roadside mechanism including a magnetic core, a winding thereon and a roadside circuit of low reluctance for said winding controlled in accordance with traffic conditions, and means for modifying the controlling condition under given traffic conditions, the said latter means comprising a plurality of vehicle carried receiving inductoriums and a plurality of roadside transmitting inductoriums cooperating therewith.

32. In a train control system, vehicle carried mechanism, means including a roadside inductor for producing a controlling condition in the vehicle carried mechanism under a predetermined traffic condition only, and means for modifying the controlling condition under given traffic conditions, the said latter means comprising a plurality of vehicle carried receiving inductors, a plurality of roadside transmitting inductors, a roadside receiving inductor cooperating with the roadside transmitting inductors and a vehicle carried energy transmitting inductor cooperating with the roadside receiving inductor.

33. Vehicle controlling apparatus including plain armatures at controlling points of the track, vehicle-carried inductive means responsively affected in passing said armatures, controlling means controlled by said inductive means, a plurality of vehicle-carried responsive devices also controlling said controlling means, and means associated with said armatures for controlling said responsive devices selectively to change the controlling conditions accordingly.

34. Vehicle controlling apparatus including plain armatures at controlling points of the track, vehicle-carried inductive means responsively affected whenever passing one of said armatures, controlling means controlled by said inductive means to obtain a predetermined condition, a plurality of vehicle-carried inductive responsive devices also controlling said controlling means, and inductive means associated with said armatures for selectively controlling said responsive devices for obtaining other conditions of said controlling means.

35. Vehicle controlling apparatus including armatures at controlling points of the track, vehicle-carried inductive means responsively affected when passing said armatures, controlling means controlled by said

inductive means, a plurality of vehicle-carried inductive coils also controlling said controlling means, and inductors on the track to selectively influence said coils to change the controlling conditions accordingly and including coils in electrical circuits and means for controlling said circuits.

36. Vehicle controlling apparatus including plain armatures at controlling points of the track, vehicle-carried inductive means responsively affected whenever passing one of said armatures, controlling means controlled by said inductive means to obtain a predetermined condition, a plurality of vehicle-carried inductive coils also controlling said controlling means, and inductors on the track for selectively controlling said inductive coils for obtaining other conditions of said controlling means and including inductive coils arranged in electrical circuits and means for controlling said circuits.

37. The method of transmitting signal impulses to a moving vehicle from the roadway of the vehicle, consisting in directing inductive magnetic energy from the vehicle, and inductively reflexing such magnetic energy back in different paths to the vehicle from the roadway under control to obtain different effects in the vehicle corresponding to the condition of control.

In testimony whereof I affix my signature,
ARCHIBALD G. SHAVER.
